(57) **CLAIM**

We claim the ornamental design for a carabiner tool with light, as shown and described.

DESCRIPTION

FIG. 1 is a perspective view of a carabiner tool with light, as viewed from the top and the right side thereof.

FIG. 2 is a side elevation view of the left side of the tool of FIG. 1.

FIG. 3 is a side elevation view of the right side of the tool of FIG. 1.

FIG. 4 is a bottom plan view of the tool of FIG. 1.

FIG. 5 is a top plan view of the tool of FIG. 1.

FIG. 6 is a rear elevation view of the tool of FIG. 1; and, FIG. 7 is a front elevation view of the tool of FIG. 1.

The broken lines shown herein are for illustrative purposes only and form no part of the claimed design.
